UNITED STATES PATENT OFFICE.

EVERETT IRVING ROGERS, JR., OF PROVIDENCE, RHODE ISLAND.

COLLAR HOLDER.

Application filed November 15, 1920. Serial No. 424,148.

To all whom it may concern:

Be it known that I, EVERETT IRVING ROGERS, Jr., a citizen of the United States, and a resident of Providence, county of Providence and State of Rhode Island, have invented certain new and useful Improvements in a Collar Holder, of which the following is a full, clear, and exact description.

Among the principal objects which the present invention has in view are: to employ roll-plated metal in the manufacture of the holder; to reduce the labor factor in the manufacture of the holder; to increase the length of movement of the portions of resilient member employed for grasping the edge of the collar; and to simplify and cheapen the construction of the holder.

Drawings.

20 Figure 1 is a side view of a holder constructed and arranged in accordance with the present invention.

Figure 2 is a side view showing the blank on which the front bar of the holder is formed.

Figure 3 is a side view of the same after it is bent in the dies to the bar shape.

Figure 4 is a rear edge view of the same.

Figure 5 is a view similar to Figure 30 4 with the clip projections bent over and folded upon each other to retain the spring bar with which the holder is provided.

Figure 6 is a side view of a spring bar used in conjunction with the front bar disclosed in Figures 2 to 5 inclusive.

Figure 7 is a side view of a modified form of the holder shown in Figure 1.

Figure 8 is a rear edge view of the same.

Figure 9 is a side view of a modified form 40 of the construction shown in Figures 7 and 8.

Figure 10 is a rear edge view of the same.

Figure 11 is a detail view showing the spring bar used in the construction shown in 45 Figures 7 and 8.

Figure 12 is a detail view showing the spring bar used in the construction illustrated in Figures 9 and 10.

Description.

50 Heretofore, collar holders have been manufactured from base metal which has been subsequently coated with relatively precious metal with processes of dipping or plating. The construction has suggested the cutting out of sheets of metal the front bars or

the bending of the front bars in various curved shapes from flat metal, to which has been attached in any suitable manner, the spring bar at the back relied upon for 60 gripping the ends or edges of the collar to be held. The use of roll-plated metal has been impossible by reason of the fact that if the first manner of forming the front bar was employed, the front edge of the 65 bar exposed the raw base metal. If the second method was employed the base metal would show at the upper and lower edges of the front bar. For these reasons the roll-plated metal has been avoided for this line 70 of manufacture. In the present invention this has been overcome by cutting sheets of plate-rolled metal, the blank 15 as seen in Fig. 2 of the drawings. The blank 15 is then struck up by a die to form a curved 75 faced edge 16 and the inturned sides 17, each of which has a clip extension 18. Between the sides 17, a channel 19 is formed wherein is disposed the open loop members 20 of the spring bar 21. The hooks 20 are 80 each provided with extensions 22 over and about which the clip extensions 18 fold when turned as seen in Figures 1 and 4 of the drawings. Between the extensions 22 of the hooks 20 and the bar 21, is a space 23 85 through which the ends of the clip extensions 18 pass. The hooks 20 have each an extended abutment heel 24 that rests in the bottom of the groove of the channel 19 to be held by the clip extensions 18 and to stiffen 90 the construction at this point.

The bar 21 is provided at the opposite ends thereof with detent teeth 25 and guide fingers 26. As shown best in Fig. 1 of the drawings the guide fingers 26 form in 95 conjunction with the extreme ends of the front bar of the holder entrances for wedging the edge of the collar past the teeth 25 to the spaces 27 between the bar 21 and the inner edge of the front bar. Thereafter the teeth 25 prevent the accidental withdrawal of the edges of the collar. As seen best in Fig. 1, the teeth 25 normally rest in the channel 19. When the collar is introduced the teeth 25 press the collar into the 100 channel 19 obtaining thereby a firmer grip on the material of the collar.

When now the holder constructed and arranged as above described is placed in service the thickened edge of the collar is forced 110 first between one end of the bar 21 and the front bar, the bar 21 yielding to permit the

displacement of the teeth 25, associated therewith. In the movement of the bar 21 it will be observed that each side thereof pivots about the loop member 20 furthest removed 5 from the teeth 25 associated with the end of the bar being deflected, the metal of the bar 21 yielding to this end between the members 20. By reason of this construction the effective flexure of the bar 21 is from each 10 of the members 20 at one side of the center of the holder to the teeth 25 at the opposite side of the center of the holder, thereby increasing, materially, the length of the yielding section of the spring bar 21 as the collar is inserted at each end of the holder. 15

It will be seen by reference to the drawings and to the description above that the front bar which is visible in service presents to the onlooker only surfaces which 20 are covered with precious metal.

In Figs. 7 and 8, a modified form of the invention is disclosed wherein a straight length of round wire is utilized to form the spring bar 28. The spring bar 28 as shown 25 is substantially straight between its extremities or between the curved portions 29 thereof, which are offset to form entrance ways for the edge of the collar between the spring bar and front bar. The ornamentations 30 30 may be employed in conjunction with the bar 28 or not.

The bar 28 is held rigidly in position by an elongation of one of the extension clips 18 to form a tubular grip 31 which retains 35 the bar 28 rigidly in position.

A further modification of the construction is shown in Figures 9 and 10 where the bar

28 is returned upon its self to form a central closed loop 32. Through this loop 32 is projected the ends of the clip extensions 18 as 40 shown best in Fig. 9 of the drawings. The sides of the loop are not secured where they overlap, therefor, the spring of each side of the bar 28 extends from the ends 29 to the further ends of the loop, thereby giving 45 greater flexibility to the bar 28.

Claims.

1. A collar holder comprising a rigid front bar constructed of a single faced metal 50 pressed to form a rearwardly opening channel, said metal having adjacent the center thereof at the rear edge, clip extensions for engaging a back bar; and a resilient back bar operatively related to said front bar and 55 providing a centrally disposed loop-like member for receiving in permanent relation said clip extensions.

2. A collar holder comprising a rigid front bar constructed of a single faced metal 60 pressed to form a rearwardly opening channel, said metal having adjacent the center thereof at the rear edge, clip extensions for engaging a back bar; and a resilient back bar operatively related to said front bar and 65 providing a centrally disposed loop-like member for receiving in permanent relation said clip extensions, said loop-like member being elongated to provide resilient areas for said back bar extending from the extremities thereof to points beyond the center thereof.

E. IRVING ROGERS, JR.
